UNITED STATES PATENT OFFICE.

EDWARD A. SRILL, OF CHICAGO, ILLINOIS.

WIRE-BOUND BOX.

1,398,606.

Specification of Letters Patent. Patented Nov. 29, 1921.

Application filed September 1, 1917. Serial No. 189,285.

To all whom it may concern:

Be it known that I, EDWARD A. SRILL, a citizen of the United States, and a resident of Chicago, in the county of Cook and State 5 of Illinois, have invented an Improvement in Wire-Bound Boxes, of which the following is a specification.

This invention relates to boxes and pertains more particularly to a novel construction of a wire-bound box.

Among other objects, the invention is intended to provide a box of desirable strength, durability, security, and tightness of closure, and capable of affording effectual protection 15 for its contents.

The general character of the invention may be understood by reference to an illustrative embodiment shown in the accompanying drawings, in which:

20 Figure 1 is a perspective of an illustrative form of box embodying the invention, the lid thereof being in open position;

Fig. 2 is a perspective of a flat blank which may be folded into the position indicated in Fig. 1 to form the exterior portions of the box. Fig. 2 is drawn on scale about one-half of that of Fig. 1.

Fig. 3 is a detached view of an end portion which may be used as shown in Figs. 30 1, 5, and 6.

Fig. 4 is a perspective of certain interior portions of the box shown in disassembled condition. The scale of Fig. 4 is approximately the same as that of Fig. 1.

35 Fig. 5 is a perspective similar to that of Fig. 1 but shown in section on a longitudinal median plane of the box and also having part of an interior wall broken away; and

Fig. 6 is a perspective similar to that 40 shown in Fig. 1 but having the lid of the box closed and showing the parts in section on a transverse vertical plane.

The box construction illustrated in Fig. 1 comprises an exterior wire-bound box element and an interior box element having 45 their corresponding walls spaced apart, the two being so assembled as to afford mutual supporting and strengthening effects. The outer structure of the box is illustrated in 50 a preferred, but non-essential, blank form in Fig. 2. The blank comprises four separate sections, 10, 11, 12, and 13, each having a sheet or piece of side material, such as

wood veneer or other suitable substance, carrying a plurality of cleats. For example, 55 the section 10 comprises five parallel cleats, 14, 15, 16, 17, and 18, and additional cleats 19 and 20 having special additional functions besides those of the other cleats, which will be described, and the other sections 60 have cleats corresponding thereto and similarly arranged.

The sections 10, 11, 12, and 13 may be entirely separate and connected by wires, as is customary in wire-bound boxes; and it 65 is preferable, in any case, when the exterior structure is made in flat blank form, that the respective side portions be flexibly connected by wires or otherwise so as to be foldable into box form. For illustration, 70 the specific sections 10, 11, 12, and 13 are connected by wires extending parallel to and in registration with the respective rows of cleats; and the wires, side sheets, and cleats are secured together by staples which 75 straddle the wires, pass through the side sheets, and enter the cleats, wherein said staples are preferably blind clenched or otherwise securely fastened.

It is desirable that the side sheets in the 80 finished box overlap at their corners to provide as tight closures as may be needed, and for this purpose the cleats and side sheets collectively may be so located relatively as to provide at each corner of the box an overlap margin of one side sheet, projecting beyond the ends of its attached cleats, which margin will overlap the edge of the adjacent side sheet when the parts are folded into box form. There are several ways in 85 which this overlapping of side sheets may be accomplished, as will appear to those skilled in the art; and, as indicated in Figs. 1, 5, and 6, such overlap margins are provided at the edges of the lid and the bottom 90 of the box so that these shall overlap the edges of the vertical front and rear sides of the box.

The wires referred to above are indicated at 21, 22, 23, 24, and 25 in several of the 100 figures.

In addition to the top, bottom, front, and rear box sections above described, the exterior structure may comprise end pieces 26, about which the box blank illustrated in Fig. 2 is folded to produce the structure shown 105

in Fig. 1. It will be seen that the end pieces 26 fit into the space between the cleats 14 and 19, and 18 and 20, respectively, and are thus firmly held in place and supported over 5 a considerable region adjacent all their edges without the necessity of stapling.

In the modification disclosed in the drawings (see particularly Figs. 1 and 5), the end pieces 26 are, prior to being assembled 10 in the completed box, firmly stapled or otherwise secured to pieces 27, which abut at one of their edges and at their bottoms squarely against the surrounding outer cleats when the box is assembled and thus materially 15 strengthen the box as well as accurately defining the folded position of the outer box blank, and at their inner vertical edges are beveled as indicated at 28 to form a convenient hand hold at their end of the box. 20 In Fig. 4 are disclosed in relatively positioned but slightly separated location the side sections of the inner box structure comprehended in my invention. These side sections comprise appropriately sized pieces of 25 veneer or other suitable material 29, which are attached at each of their ends to a cleat 30, preferably having the usual mortise and tenon construction at their ends. When the structure shown in Fig. 4 is assembled, so 30 that the mortises and tenons engage, there will be provided an open-ended box structure having the cleats outside. This box structure is placed within the outer box structure disclosed in Fig. 1 and made from 35 the blank shown in Fig. 2, to form the inner box. The ends of the inner box are formed of loose, appropriately sized sheets of veneer 31, which are placed within the cleats 19 and 20 respectively, and in the assembled structure 40 are held in position by the cleats 19 and 30 at one end, and the cleats 20 and 30 at the other end. The end pieces 26 and 31 fit, when the cover is closed, between the cleats on the cover section, and are held and supported thereby in precisely the same manner 45 as they fit in between and are supported by the cleats on the remaining sections of the outer box blank.

It will be apparent, therefore, that the 50 cleats 15, 16, and 17 serve not only to reinforce and strengthen the box structure as a whole but also serve as spacing elements to space the inner box structure from the outer box structure. The same function is effected 55 by the cleats 30, which, because they are attached to the inner box structure, directly support and strengthen it, but also support and strengthen the outer box structure in the same manner as the cleats 15, 16, and 17. 60 These cleats 30 also serve as spacing means. The cleats 19 and 20 serve to strengthen and support the outer box structure in the ordinary fashion of cleats in this art. They serve furthermore to space the end sections 26 and 31

while the cleats 14, 19, and 30, on one end of the box, and 18, 20, and 30, on the other end of the box, two of each group of which are secured to the outer box sections and one to the inner box section, serve to strongly reinforce, 70 space and support both pairs of end sections of the box.

The box of my invention may be shipped and stored in knock-down form, the box blank section shown in Fig. 2 being capable 75 of being laid flat or folded quite flat to take one-half the space which it takes when laid flat; the inner side sections 29—30 are separate and may be laid flat and the end pieces 26 and 30 may also be laid flat, all contributing 80 to provide a box which in knock-down form takes up a minimum of space. The box of my invention may also be assembled manually without the use of nails or staples. After being assembled, as indicated in Fig. 85 1, the cover is closed and the projecting ends of the wire 21, 22, 23, 24, and 25 twisted together, as indicated at 33 (Fig. 6) in the usual manner of wire-bound boxes.

The box of my invention has all of the 90 characteristics of strength of the ordinary wire-bound box, supplemented and reinforced by the fact that additional cleats are provided therein, and affords a double-wall 95 container, every part of which is adequately supported and reinforced against strain of any kind. The box has valuable insulating properties to prevent sudden changes of temperature in or the penetration of moisture to its contents and is particularly useful in 100 connection with the shipping of explosives, because hooks or the like, when used, cannot damage or puncture the contents of the inner box.

Having now described my invention, I 105 claim:—

1. A wirebound double-walled box comprising outer side and end walls composing the exterior of the box; inner side and end walls forming an interior inclosure; cleat frames relatively positioning said several walls, certain of said cleat frames mutually reinforcing the outer and inner side walls; and bindings secured to and around the 110 box.

2. A box comprising, in combination, reinforcing cleats and side walls arranged in parallel upon opposite sides of and contiguous to a plurality of cleats, one wall attached to certain of said cleats and the other 115 attached to and removable with certain other of said cleats.

3. A box comprising cleats, inner and outer side walls, and inner and outer end walls, said cleats relatively positioning said 120 several walls, certain of said cleats attached to the inner surfaces of said outer side walls, and certain of said cleats attached to the outer faces of said inner side walls.

4. A box comprising side walls and cleats, 125

certain of said cleats spacing apart two such side walls arranged in parallel on opposite sides of and contiguous to said certain cleats, and outer and inner end walls arranged on opposite sides of certain of said cleats.

5. A box comprising side walls and cleats, additional side walls, some of said cleats enclosed between said first-mentioned and additional side walls and said walls respectively secured to certain of said cleats, and end walls and additional end walls located in alternation with certain of said cleats.

10. A box comprising an outer box element, an inner removable box element having external cleats forming surrounding frames, said cleat frames fitted within and serving to space the inner box element from the outer box element.

15. A box consisting of an outer box element comprising side pieces and cleats secured to the inner surfaces thereof, and a removable inner box element comprising side pieces and cleats secured to the outer surfaces thereof, certain of said cleats serving to space inner box side pieces from outer box side pieces.

20. A box comprising a wire-bound outer box element having side pieces and reinforcing cleats, certain of said cleats being located in contiguous planes to support opposite faces of end sections or the like, end sections supported by said cleats, additional end sections located contiguously to certain of said first end section supporting cleats, and an inner box element providing means to hold said additional end sections so contiguous.

25. A box comprising an outer box element having side pieces with cleats secured thereto, an inner box element having inner side pieces and other cleats secured thereto, certain of the cleats of said inner and outer box elements respectively being located in two contiguous planes whereby an end piece or the like may be inserted between and supported by the cleats in said planes.

30. A box comprising an outer box element and an inner box element, both including side pieces and cleats secured thereto, certain of said cleats at either end of the box being arranged in three contiguous planes, whereby two spaced end sections may be inserted between and supported by the cleats in said planes at either end of the box.

35. A box comprising a plurality of cleat frames; exterior and interior side walls; said exterior side walls inclosing said plurality of cleat frames; outer and inner end walls secured in position by certain of said cleat frames; and said interior side walls inclosed by the cleat frames intermediate said inner end walls.

40. A box comprising a plurality of par-

allel cleat frames, outer and inner side walls, 65 and outer and inner end walls, said cleat frames relatively positioning said several walls, and certain of said walls secured to certain of said cleat frames.

45. A box consisting of an outer box element comprising cleats and side walls attached thereto; an inner box element comprising cleats and side walls attached thereto; cleats of both elements spacing the walls of said outer from those of said inner element in the completed box; and cleats of said outer element coöperating with cleats of said inner element to prevent relative longitudinal shifting of said elements.

50. A wirebound box comprising a plurality of cleat frames; exterior side walls inclosing said frames; interior side walls inclosed within some of said frames; and inner and exterior end walls associated with a plurality of cleat frames at each end of the box, and bindings around the box securing the parts together.

55. A wirebound double-walled box comprising outer side and end walls composing the exterior of the box; inner side 90 and end walls forming an interior inclosure; end cleats associated with the end walls and providing interior reinforcing frames for said outer side walls; a plurality of intermediate cleats reinforcing the outer side 95 walls internally and reinforcing the inner side walls externally; and bindings secured to and around the box.

60. A box consisting of an interiorly cleated wirebound outer box element, and an exteriorly cleated inner box element, cleats of said inner element interiorly reinforcing said sides of said outer element, and cleats of said outer element exteriorly reinforcing the sides of said inner element.

65. A set of box parts comprising a foldable wirebound box blank to form an outer box element, said blank having foldably-related end cleats and intermediate cleats, a plurality of separate inner side sections to 105 form an inner box element adapted to be inclosed and externally reinforced by cleats of said blank when the latter is folded into box form, and end sections for the inner and outer box elements, all adapted to be assembled into the form of a double-walled rigid wirebound container without the use of nails or their equivalents.

70. A wirebound double-walled box comprising, in combination, an outer box structure comprising side walls, end walls and reinforcing cleats; an inner box structure having exterior end cleats fitting within the outer box structure; cleats of the inner and outer structures coöperating to prevent relative longitudinal shifting of said structures; and bindings secured to and around said outer structure.

19. A wirebound box comprising cleated side sections and bindings secured to and foldably connecting them; end walls around which said sections are folded; removable inner end walls spaced from the first mentioned end walls; an inner box element between the inner end walls; and means for

spacing said element from the four sides of the outer box formed by said foldably-related sections.

10

In testimony whereof, I have signed my name to this specification.

EDWARD A. SRILL.
